(57) **CLAIM**

The ornamental design for an “image input apparatus for an electronic game machine”, as shown and described.

DESCRIPTION

FIG. 1 is a front elevational view of an image input apparatus for electronic game machine according to my design;

FIG. 2 is a rear elevational view thereof;

FIG. 3 is a top plan thereof;

FIG. 4 is a bottom plan view thereof;

FIG. 5 is a right side elevational view thereof; and,

FIG. 6 is a left side elevational view thereof.
